CLAIM

The ornamental design for a extension tip for handling objects such as hanging plants and the like, as shown and described.

DESCRIPTION

FIG. 1 is a front elevational view of a extension tip for handling objects such as hanging plants and the like showing my new design, the rear elevational view being a mirror image thereof;

FIG. 2 is a side view, taken from the left side of FIG. 1, the right side view being a mirror image thereof;

FIG. 3 is a top plan view thereof;

FIG. 4 is a bottom plan view thereof;

FIG. 5 is an enlarged cross-sectional view thereof, taken along line 5—5 in FIG. 1; and,

FIG. 6 is a perspective view thereof.

The broken line showing a handle in FIG. 6 is for illustrative purposes only and forms no part of the claimed design.
